POCKET HATRACK

Shefford L. Keene and Richard T. Palmer,
Hampton, Va.

Application June 22, 1951, Serial No. 232,972

3 Claims. (Cl. 24-3)

1

This invention relates to hat racks, and more particularly to a personal hat rack adapted to be carried in the pocket of the wearer.

A main object of the invention is to provide a novel and improved personal hat rack device which is simple in construction, which is neat in appearance, and which is normally maintained in an out-of-the-way position.

A further object of the invention is to provide an improved personal hat rack device adapted to be carried in the wearer's pocket and which normally has the appearance of a pen and pencil set, but which may be readily swung to an outwardly extending position to receive the user's hat and to support same as long as desired, the device being inexpensive to fabricate, having only a few parts, being sturdy in construction, and having an ornamental appearance.

Further objects and advantages of the invention will become apparent from the following description and claims, and from the accompanying drawings, wherein:

Figure 1 is a view of a person, showing an improved hat rack device according to the present invention engaged in the wearer's pocket and arranged in an outwardly extending position to receive the wearer's hat;

Figure 2 is an enlarged top plan view of the hat rack device illustrated in Figure 1;

Figure 3 is an enlarged front elevational view of the improved hat rack device;

Figure 4 is a vertical cross-sectional view taken on the line 4-4 of Figure 3;

Figure 5 is a vertical cross-sectional view taken on the line 5-5 of Figure 2;

Figure 6 is a horizontal cross-sectional view taken on the line 6-6 of Figure 5;

Figure 7 is a horizontal cross-sectional view taken on the line 7-7 of Figure 3;

Figure 8 is a vertical cross-sectional view taken on the line 8-8 of Figure 7, but showing the internal construction of the lower portion of the hat rack stud locking member.

Referring to the drawings, the hat rack device is designated generally at 11, and comprises a pair of parallel, tubular body members rigidly connected together in spaced relationship by the spaced, parallel, flat bar members 14 and 15. A hinge arrangement includes a tubular cap 16 which is shouldered at 17 and which is telescopically engaged in the body member 12. Secured transversely in the upper portion of the cap member 16 is a pin 18 to which is connected one end of a coil spring 19, the other end of said spring being connected to a tapered plug 20

2

engaged in the lower end of the tubular body member 12. Designated at 21 is a hollow stud member which is rigidly secured to cap 16 by a flat bar member 22 and which is spaced at the same distance from the cap member 16 as the body member 13 is spaced from the body member 12. The hollow stud member 21 has a relatively thick bottom wall 23 which is formed with a recess 24. Pivoted at diametrically opposite points in the top portion of the body member 13 is a semicircular yoke 25 formed at its mid-portion with an upstanding lug 26 lockingly engageable in the recess 24, as shown in Figure 3. The mid-portion of the yoke 25 is formed with an outwardly extending shank element 27 which passes through a vertical slot 28 formed in the wall of body member 13, said shank having secured to its end a head 29. Encircling the shank is a coil spring 30 which bears between head 29 and the outer surface of body member 13 and exerts frictional binding force which serves to maintain the yoke 25 in a desired adjusted position. For example, when the yoke is in its uppermost position, the lug 26 is engaged in the recess 24 and holds the stud 21 in alignment with the body member 13. When the head 29 is depressed, causing the yoke 25 to be swung downwardly, the lug 26 is disengaged from the recess 24, releasing the stud element 21 and allowing said stud element to be swung outwardly, for example, to the dotted view position of Figure 2, whereby the connecting bar 22 is substantially at right angles to the plane of the body members 12 and 13. The rim of the body member 13 is formed with an upstanding lug 31 located opposite the lug 26, the lug 31 serving as a stop means to limit the return movement of the stud element 21 to a position wherein it is in axial alignment with the body member 13, and in which it may be secured by the locking engagement of lug 26 in recess 24.

The body members 12 and 13 are provided with respective pocket-engaging clip members 32 and 33, whereby the body members 12 and 13 may be secured in the wearer's pocket in side-by-side relationship, and whereby the elements 16 and 21 appear to be the upper portions of a pen and pencil set, under normal conditions. As shown in Figure 3, the connecting bar 22 may be suitably decorated with the wearer's initials or monogram.

As shown in Figure 1, when it is desired to employ the device to support the wearer's hat, the wearer releases the stud element 21 by depressing the head 29, whereby the stud element 21 may be

swung outwardly to a forwardly projecting position, as shown in Figure 1, whereupon the wearer's hat may be hung on the stud element 21, as shown in dotted view.

The hollow stud element 21 may be employed to house a cigarette lighter 34, the said stud element being provided with the detachable top cap 35 affording access to the cigarette lighter 34. The body member 13 may be formed with a second wall element 36 which may be centrally apertured to support a removable plug 37 of suitable deformable resilient material, such as rubber or the like, said plug being formed with a central slot in which a nail file 38 is secured. Access to the plug 37 is provided when the stud element 21 is swung to an outwardly projecting position exposing the top end of the body member 13.

The coil spring 19 biases the hinge cap 16 toward the body member 12, and at the same time biases the stud element 21 toward the body member 13, thereby preventing accidental disengagement of the stud element 21 from the securing lug 26.

While a specific embodiment of an improved personal pocket hat rack has been disclosed in the foregoing description, it will be understood that various modifications within the spirit of the invention may occur to those skilled in the art. Therefore, it is intended that no limitations be placed on the invention except as defined by the scope of the appended claims.

What is claimed is:

1. A pocket hat rack comprising a pair of parallel body members, means rigidly connecting said body members in spaced relation, a hinge member rotatably secured on one body member, a stud member, means rigidly connecting said stud member to said hinge member and arranged to at times support said stud member in a posi-

tion axially aligned with said second body member, and releasable latch means on said second body member arranged to lockingly secure said stud member in said axially aligned position.

2. A pocket hat rack comprising a pair of parallel body members, means rigidly connecting said body members in spaced relation, a shouldered cap member rotatably engaged in one body member in coaxial relation therewith, a stud member, means rigidly connecting said stud member to said cap member and arranged to at times support said stud member in a position axially aligned with said second body member, releasable latch means on said second body member arranged to lockingly secure said stud member in said axially aligned position, and spring means securing said cap member to said one body member.

3. A pocket hat rack comprising a pair of parallel, tubular body members, means rigidly connecting said body members in spaced relation, a shouldered cap member rotatably engaged in one body member in coaxial relation therewith, a hollow stud member, means rigidly connecting said stud member to said cap member and arranged to at times support said stud member in a position axially aligned with said second body member, releasable latch means on said second body member arranged to lockingly secure said stud member in said axially aligned position, and a coil spring arranged axially in said one body member and connected at its ends respectively to said one body member and said cap member, said spring being arranged to bias the cap member and the stud member toward engagement with the respective body members.
